(57) **CLAIM**

The ornamental design for a heat press, as shown and described.

DESCRIPTION

FIG. 1 is a front perspective view of a heat press, showing my new design;

FIG. 2 is a front view thereof;

FIG. 3 is a rear view thereof;

FIG. 4 is a first side view thereof;

FIG. 5 is a second side view thereof;

FIG. 6 is a top plan view thereof; and,

FIG. 7 is a bottom plan view thereof.

The broken lines show portions of a heat press that form no part of the claimed design.

The broken lines in FIGS. 4-7 represent a symbolic break in the length of the cord of a heat press, and form no part of the claimed design.
